UNITED STATES PATENT OFFICE

ERWIN R. STOEKLE, OF MILWAUKEE, WISCONSIN, ASSIGNOR TO CENTRAL RADIO LABORATORIES, OF MILWAUKEE, WISCONSIN, A CORPORATION OF WISCONSIN

VARIABLE RESISTANCE

Application filed June 11, 1927. Serial No. 188,014.

This invention relates to a variable resistance adapted for use as a rheostat or as a single or double potentiometer.

In variable resistances of this character as heretofore proposed the resistance element or resistor was mounted on an insulating base in the form of a disk or panel, and this same insulating base was constructed and equipped to serve as a support for the shaft or arbor carrying the contact shoe co-operable with the resistor. Such a construction is relatively heavy, awkward to handle and mount, and is not only complicated and more or less difficult to produce, especially 15 as regards its assembly, but is also comparatively expensive.

One of the objects of the present invention resides in the elimination of the insulating base and the avoidance of the disadvantages incident to the production and use thereof.

In carrying out the present invention, the resistor is mounted on and insulated from a split core, usually annular in form, and the shaft or arbor carrying the contact shoe is supported from the core of the resistor. Preferably, the shaft or arbor is supported in a bearing provided at the inner end of a radial arm, the outer end of which radial 25 arm is firmly and rigidly secured to lugs integral with the ends of the annular core located at the split provided therein. The lugs which thus serve as a convenient means for fastening the arm to the core, also provide a convenient mounting means for the 30 binding posts employed to connect the contact shoe and the resistor with the circuits or the instrumentalities with which they are associated. Usually two binding posts are mounted on the lugs of the core, but provision is made for the mounting of a third binding post on an extension of the arm. By providing for the mounting of three 35 binding posts the resistance may be utilized as a rheostat, in which case only two binding posts are utilized, or may be employed as a potentiometer, in which event all three binding posts are employed. The contact shoe employed when the device is utilized 40 as a rheostat or as a potentiometer coacts

with the bends of the turns of the resistor located around one edge of the core. By employing a second contact shoe insulated from the arbor though mounted thereon and located to coact with the bends of the turns 55 at the opposite edge of the core, the resistor may also be employed as a double potentiometer. The arm which supports the sleeve receiving the shaft or arbor for the contact shoe of the rheostat or potentiometer 60 preferably has bendable lugs integral therewith and adapted for use as stops for the contact shoe, and also adapted to be bent to lift the contact shoe out of engagement with the resistor for interrupting the circuit 65 should this be desirable.

Other objects and advantages reside in certain novel features of the construction, arrangement and combination of parts which will be hereinafter more fully described and 70 particularly pointed out in the appended claims, reference being had to the accompanying drawings forming a part of this specification, and in which:

Figure 1 is a view in rear elevation showing one embodiment of the invention when used as a rheostat; 75

Figure 2 is a view in section taken on line 2-2 of Figure 1;

Figures 3, 4, and 5 are detail sectional 80 views taken on lines 3-3, 4-4 and 5-5 respectively of Figure 1;

Figure 6 is a view in rear elevation showing the device adapted for use as a potentiometer; 85

Figure 7 is a fragmentary detail sectional view taken on line 7-7 of Figure 6 with parts shown in elevation for the sake of illustration;

Figure 8 is a similar view taken on line 8-8 of Figure 7; 90

Figure 9 is a view in rear elevation illustrating the device when used as a grid bias, as well as a rheostat or potentiometer; 95

Figure 10 is a sectional view taken on line 10-10 of Figure 9;

Figure 11 is a detail perspective view of the core;

Figure 12 is a similar view of the arm; 100

Figure 13 is a similar view of the contact shoe employed for the grid bias; and

Figure 14 is a detail view in elevation of the sleeve supported at the inner end of the 5 arm and adapted to receive the arbor or shaft.

Referring to the drawings, it will be seen that in all embodiments of the invention a split annular core 1 is provided, the core 1 being constituted of metal which is an electrical conductor and which is sufficiently bendable to permit it to be shaped as described, although in the assembly the core is substantially rigid. At the split in the core 10 outwardly directed lugs 2 are provided. In between the lugs 2 the outer end of a radial connecting and supporting arm 3 is positioned and firmly and securely fastened in any suitable way, as for instance, by welding and also by the action of the fastening 15 means for the binding posts to be later described. The arm 3 is doubled upon itself and at its inner end has a bight 4 shaped to receive and embrace a bearing sleeve 5. The 20 sections of the arm 3 are secured together by a spot weld 6, and this spot weld has been found sufficient to cause the bight portion 4 of the arm to clamp and firmly grip the portion of the sleeve 5 fitted therein whereby the sleeve 5 is fixed to the arm. A shaft 25 or arbor 7 is rotatably fitted in the sleeve 5. As shown in Figures 2 and 10, the shaft 7 has a shoulder 8 limiting endwise movement of the arbor 7 in the sleeve 5 in one direction. Endwise movement of the arbor 30 7 in an opposite direction is prevented by the action of a contact shoe 9 secured as at 10 to the end of the arbor opposite the shoulder 8. This contact shoe 9 is somewhat resilient and is tensioned to engage or press 35 against the resistance element or resistor 11 which consists of a wire wrapped around insulation 12 covering the core 1. The turns of the wire 11 are spaced from each other 40 and the contact shoe 9 coacts with the bends 11^a of the turns located around one edge of the insulation covered core. To facilitate 45 the sliding adjustment of the contact shoe 9 over the turns of the resistor 11, the edge 50 portions of the contact shoe which engage the resistor are deflected or beveled as indicated at 9^a in Figure 5.

When the device is employed as a rheostat, one end of the wire 11 is connected to a 55 binding post designated generally at 13. The binding post 13 comprises a small terminal piece 14 mounted on a rivet 15 and adapted for connection to an outside current or the like. The rivet 15 extends through 60 flanged insulating bushings 16 which line the openings provided in the lugs 2 and arm 3 to receive the rivet 15 and the bushings 16. The head 15^a of this rivet 15 clamps the 65 wire 11 between it and the terminal piece 14. The end of the rivet 15 opposite the

head 15^a is swaged over as at 17 against a metallic washer 18 engaging the adjacent end of the adjacent fiber bushing 16. This construction is clearly shown in Figure 3. In this way the terminal piece 14 is electrically connected with one end of the wire 11, but this end of the wire 11 is electrically insulated from the other elements of the device. The opposite end of the wire 11 is tied as at 19 (see Figure 4) to an adjacent 70 turn and thus the resistor ends on the insulation 12 without outside electrical connection.

To provide for an electrical connection of the contact shoe 9 with outside points, a binding post designated generally at 20 is provided on the lugs 2 of the core. The binding post 20 comprises a terminal piece 21 of the same construction as the terminal piece 14. This terminal piece 21 is clamped between the head 22^a of a rivet 22 and the adjacent lug 2 of the core. The end of the rivet opposite the head 22^a is swaged over against the adjacent lug 2 of the core. As no insulating bushings or washers are provided between the terminal piece 21 and the lugs of the core, the terminal piece 21 is electrically connected with the lugs of the core and with the arm 3 engaged with these lugs. With the arrangement described, the 95 current may flow from the binding post 13 through the wire 11 to the contact shoe 9, through the contact shoe 9 to its arbor 7, the sleeve 5, the bight portion 4 of the arm 3, and then through the arm 3 to the lugs 2 and binding post 20. By shifting the contact arm 9 around the core more or less resistance may be interposed in the circuit.

The arm 3 may have its sections provided with bendable lugs 24 and 25, the lugs 24 and 25 being adapted to serve as stops, and also as means for disengaging the contact shoe from the resistor. As illustrated in Figures 1 and 4, the lugs 24 may be bent at an angle to the arm 3, while the lug 25 is left in the same plane as its section of the arm 3. With this arrangement the lug 25 serves as a stop for limiting the angular movement of the contact shoe 9. The lug 24 on the other hand has its outer end rounded or beveled off as indicated at 24^a whereby to facilitate the beveled contact shoe riding up on to the lug 24, in which position the contact shoe is held in spaced relation to the turns of the wire 11 to interrupt the circuit.

When the device is used as a single potentiometer a third binding post designated generally at 26 is provided and is mounted on apertured extensions 27^a of the arm 3. The binding post 26 consists of a terminal plate 27 mounted on a rivet 28 and engaging the opposite end of the wire 11 from that engaged with the terminal plate 14. The end of the wire 11 engaged with the terminal plate 27 is clamped between plate 130

27 and the head 28^a of the rivet 28. The opposite end of the rivet is swaged over a metallic washer 29 which bears against one end of one of a pair of flanged insulating bushings 30, the insulating bushings 30 serving to insulate the rivet 28 from the ears 27^a of the arm 3. In using the device as a potentiometer, the binding posts 13 and 26 are incorporated in the circuit containing 10 the source of current. The binding posts 20 and 26 are connected to the circuit upon which the variable voltage is to be impressed. By shifting the contact shoe 9 the value of 15 the resistance interposed between the source of current and the circuit to be energized is varied, and consequently a variable voltage is had.

As shown in Figure 2, the sleeve 5 has an externally threaded portion 35 projecting 20 beyond the bight portion 4 of the arm 3, and in use this externally threaded portion 35 may be extended through an opening provided therefor in a panel 36. One or more nuts 37 may be threaded on the portion 35 25 of the sleeve for clamping the device in position on the panel. An operating knob 37 is suitably fixed to the portion of the shaft 7 projecting beyond the sleeve.

The device may be used as a double potentiometer by providing a second contact shoe 38. The contact shoe 38 has an eye 39 at its inner end, and this eye 39 is bushed by the flange of an insulating washer 40, the washer 40 abutting the adjacent end of the 35 bight portion 4 of the arm 3. The opposite side of the shoe 35 is engaged by an insulating washer 41 which is forced up against the shoe by nut 42 threaded on the sleeve 5. In this way the shoe is not only mounted 40 on and insulated from the sleeve 5, but is frictionally held in any adjustment. The portion of the shoe which engages the resistor has beveled edges 43. The outer end of the shoe is provided with an angular 45 extension 44 containing an operating knob 45. This angular extension 44 has a flexible wire 46 soldered thereto whereby the shoe is connected up with the instrumentalities with which it is associated.

50 The hook-up forms no part of the present invention and hence the adaptability of the device for its various connections is only generally indicated.

It is to be noted that the same resistor 55 presents opposite edge portions so as to be adapted to coact with two contact shoes, thereby enabling the use of the device as a rheostat or a single or double potentiometer.

The invention claimed is:

60 1. A device of the character described comprising a substantially annular core, insulation on the core, a resistor wrapped around the core, contact shoes cooperable with the opposite edge portions of the resistor, and a mounting for the contact shoes

supported from the core, said contact shoes being electrically insulated from each other.

2. A device of the character described comprising a substantially annular core, insulation on the core, a resistor wrapped around the core, contact shoes cooperable with the opposite edge portions of the resistor, an arm directly and rigidly secured to the core, and a sleeve at the inner end of the arm for supporting the contact shoes, 70 said contact shoes being electrically insulated from each other.

3. A device of the character described comprising a split annular core, an arm rigidly and directly secured to the core at 80 the split, a shaft supported by the arm, a resistor mounted on and insulated from the core, and a contact shoe mounted on the shaft and cooperable with the resistor, and two bendable lugs on the arm, one disposed 85 to limit the movement of the contact shoe in one direction and the other disposed to lift the contact shoe out of engagement with the resistor.

4. A device of the character described 90 comprising a sleeve, a split annular core concentrically disposed with respect to said sleeve and having outturned lugs at its split, a radial connecting arm doubled upon itself and having a bight at its inner end embracing and secured to the sleeve, the outer end of the radial arm being secured between the lugs of the core, a resistor mounted on and insulated from the core, and a contact shoe mounted on the sleeve and engageable with 95 the resistor.

5. A device of the character described comprising a sleeve, a split annular core concentrically disposed with respect to said sleeve and having outturned lugs at its split, 105 a radial connecting arm doubled upon itself and having a bight at its inner end embracing the sleeve, a weld between the portion of the arm adjacent the sleeve whereby the arm is fixed on the sleeve, the outer end of the radial arm being secured between the lugs of the core, a resistor mounted on and insulated from the core, and a contact shoe mounted on the sleeve and engageable with 110 the resistor.

6. A device of the character described comprising a split annular core, an arm rigidly and directly secured to the core at the split, a shaft carried by the arm, a resistor mounted on and insulated from the 120 core, a contact shoe mounted on the shaft and engageable with the resistor, and bendable lugs on the arm and engageable with the contact shoe.

7. A device of the character described 125 comprising a split annular core of conductive material, said core having integral outturned lugs at the split, an arm of conductive material having its outer end directly secured to and between the lugs of the core, 130

a sleeve of conductive material carried by the arm and electrically connected therewith, a covering of insulation on the core, a resistor wrapped around the insulation of the core, a contact shoe mounted on and electrically connected with the sleeve and engageable with the resistor, and binding posts mounted on the lugs, one of the binding posts being insulated from the lugs and electrically connected with the resistor, the other binding post being electrically connected with the contact shoe through the lugs, arm and sleeve.

8. A device of the character described comprising a split core formed with offset lugs at its split, an arm having a portion disposed between said lugs, a resistor mounted on and insulated from the core, a shaft carried by the arm, a contact shoe mounted on the shaft and engageable with the resistor, binding posts for the resistor and contact shoe, and rivets coacting with the lugs, arm and binding posts for clamping and rigidly securing the lugs to the arm and for mounting the binding posts in position on the lugs.

9. A device of the character described comprising a split core having transversely extending lugs at its split, a resistor mounted on and insulated from the core, a radial arm doubled upon itself and having a bight at its inner end provided with bearing means, the outer end of the radial arm being secured between the lugs of the core, a shaft mounted in the bearing means of the arm and a contact shoe mounted on the shaft and engageable with the resistor.

In witness whereof, I hereto affix my signature.

ERWIN R. STOEKLE.
